UNITED STATES PATENT OFFICE

147,471

DESIGN FOR AN AIRCRAFT INSTRUMENT

Oliver V. Phillips, Denver, Colo.

Application August 13, 1945, Serial No. 121,397

Term of patent 3½ years

(Cl. D52—1)

To all whom it may concern:

Be it known, that I, Oliver V. Phillips, a citizen of the United States of America, residing at Denver, in the county of Denver and State of Colorado, have invented a new, original, and ornamental Design for Aircraft Instruments, of which the following is a specification, reference being had to the accompanying drawing, forming a part thereof.

Figure 1 is a front elevation of an aircraft instrument, showing my new design,

Figure 2 is a side elevation thereof,

Figure 3 is a plan view of the same, said view being a top plan, it being noted that a bottom plan view would appear substantially identical, and

Figure 4 is a rear perspective view of the instrument.

I claim:

The ornamental design for an aircraft instrument, as shown and described.

OLIVER V. PHILLIPS.
